UNITED STATES PATENT OFFICE.

SAGER CHADWICK, OF PHILADELPHIA, PENNSYLVANIA, ASSIGNOR, BY
MESNE ASSIGNMENTS, TO THE CHADWICK COPYING BOOK COMPANY,
OF TRENTON, NEW JERSEY.

LETTER-COPYING BOOK.

SPECIFICATION forming part of Letters Patent No. 391,299, dated October 16, 1888.

Application filed October 6, 1883. Serial No. 108,361. (No model.)

To all whom it may concern:

Be it known that I, SAGER CHADWICK, of the city of Philadelphia, in the county of Philadelphia and State of Pennsylvania, have in-

5 invented certain new and useful Improvements in Letter-Copying Books; and I do hereby declare that the following is a full, clear, and exact description thereof, reference being had to the accompanying drawings, in which—

10 Figure 1 shows a plan view of my book laid open, the impervious sheets or pads used with it not being shown; Fig. 2, an end view of my book as ready for use, but closed; Fig. 3, a similar view of the same open, showing the 15 manner of using the book when making a copy; and Fig. 4, a detail perspective view of the moistening-pad, reduced in size.

Letters of like name and kind refer to like parts in each of the figures.

20 My invention has reference to means for copying letters.

Where it has been attempted heretofore to keep a number of the pages of a copying-book wet at a time and ready for use, such pages 25 have in a short time become moldy and ill-smelling, and the binding of the book has been acted upon and ruined by the moisture reaching it from the pages. Another difficulty with most of the copying-books in which the 30 leaves are kept wet ready for use has been that the moisture passing throughout and permeating the whole extent of the leaves or pages has made it difficult to separate such pages as are wanted for a copying operation. Often 35 where the pages are quite damp it has been impossible to separate them without danger of tearing.

The object of my invention is to provide a copying-book free from all these objections, 40 which shall not require either press, special ink, special paper, or a brush and water-bowl, in which any desired number of pages or leaves can be kept moist at once without danger of molding or deterioration or of injuriously affecting the binding, and in which any 45 of the moist leaves can always be readily and quickly separated from the rest for use without delay, and without danger of tearing.

With these ends in view my invention consists, principally, in the book and the parts

thereof arranged and combined, and having the nature and peculiarities, as hereinafter specified, and more specifically pointed out in the claims.

It consists, further, in the method of treating and preparing the leaves or pages of the book, as hereinafter specified, and pointed out in the claims.

In the drawings, A A designate the sheets or leaves of my book, and B B the binding and 60 covers thereof. Said sheets or leaves are made of any desired kind of light paper, and are treated with a substance which will enable them to absorb moisture readily. For such substance I contemplate using chloride 65 of sodium, acetate of potash, chloride of calcium, or any other desired hygroscopic material. I also contemplate using glycerine, either alone or in combination with either of the chemicals mentioned above. The sheets 70 or leaves treated or saturated with any of said chemicals, or with the mixture of one of them with glycerine, are in condition to absorb most easily any moisture applied to them, so that said moisture will be distributed evenly and 75 thoroughly throughout the sheets. To prevent any possibility of mold or mildew when the sheets are wet, I treat them with an antiseptic—as, for instance, bichloride of mercury or salicylic acid. Such antiseptic can be added 80 to the solution of moisture-absorbent chemical before the sheets are saturated therewith, or the paper may be impregnated with the antiseptic after treatment with the moisture-absorbent.

As any moisture applied to the leaves of the book spreads in all directions, it is necessary to provide some means for keeping it away from the binding of the book, or from those portions of the leaves which are engaged and 90 held by the binding devices. Such edges or portions of the leaves are therefore treated with a substance impervious to or non-absorbent of water. The moisture held by and saturating the rest of the sheet will not pass or 95 affect the portion of the sheet treated with this substance, and so cannot reach and affect the binding and will not weaken the edge of the sheet or that portion engaged by the binding devices. The substance which I contemplate 100

using for this purpose consists of beeswax, paraffine, and turpentine, preferably in the proportions of one ounce each of beeswax and paraffine and a half-pint of turpentine. The wax and paraffine are melted together and the turpentine is added, the mixture being kept in liquid condition for use.

I do not limit myself to this particular mixture for rendering portions of the sheets impervious to moisture. Other mixtures and substances can obviously be used for the same purpose without departure from this part of my invention.

To prevent the leaves when moist from sticking together, and to make them easily separable to turn them, as desired for use, I treat them at one or more places—as, for instance, at the corners *a a*—with the substance impervious to moisture, so that such places or portions of the leaves will not become saturated with moisture, and so will not stick together or tear easily. The substance used may be applied to any desired parts of the leaves, either by brushing or printing it on the leaves, or by dipping said parts of the latter into the substance. The back of the book can be still further protected from moisture, if desired, by a strip or band, C, of rubber or other material impervious to moisture.

To properly moisten the leaves of my book and keep any desired number of the leaves moist and ready for use, I use a moistening-pad, D, consisting, preferably, of several sheets of blotting-paper sewed together, as shown at *d* in Fig. 4. This pad, after being moistened with water, is laid on an impervious pad, E, adapted to keep its moisture from being imparted to the leaves back of or beyond those desired to be moistened. The latter leaves (those to be moistened) are then turned and laid upon the moistening-pad and a second impervious or water-proof pad or sheet, F, is placed on top of them. The book is then closed, as shown in Fig. 2. In a short time all the leaves on top of the moistening-pad, prepared as they are, will absorb from the latter enough moisture to put them in proper condition for copying, and such moisture will be kept up and retained in them all for a long time, so that the book will be ready for use without further moistening. The parts treated with the substance impervious to moisture are not saturated, like the other portions of the leaves, with the moisture from the pad, but remain substantially unaffected thereby.

In using my book for copying the book is opened and the page or leaf next to the pad F is by its unsaturated corner *a* (rendered impervious to moisture, as described) easily separated from the rest and lifted up. A third water-proof pad, G, is placed under the raised leaf and upon the saturated leaves below. The letter to be copied is then placed between the pad G and the leaf and the pad F is pressed down upon them. Without a press, if the hand or a piece of hard substance be passed over and pressed upon the pad F, a clear and

distinct copy of the letter will be taken in a very short time.

For each new page used the above-described process is repeated.

As desired or found necessary, the moistening-pad can be removed and replaced farther back in the book to moisten additional leaves.

I do not limit myself to any particular way of manipulating the letter to be copied and the leaf and water-proof pads. If desired, of course the leaf can be turned over to rest upon the front pad, the letter be placed face down upon the leaf, and the second pad be placed and pressed against the back of the letter.

There are several ways in which the copying can be done with my book, as described. As the leaves are already prepared and moistened, several copies of a letter can easily and quickly be taken in succession.

I do not limit myself to any particular absorbent or hygroscopic material for saturating the paper, nor to any particular kind of substance or compound for rendering portions of the sheets impervious to moisture.

I contemplate making the moistening-pad of any fibrous material, as felt; but I prefer blotting-paper, as it acts well and is cheap.

Having thus described my invention, what I claim is—

1. A copying-book having the inner parts of the leaves next the binding made impervious to moisture, substantially as and for the purpose shown.

2. A copying-book the leaves of which are impregnated with an absorbent for moisture and have their inner parts at the binding treated with a substance adapted to make such parts impervious to moisture, substantially as and for the purpose described.

3. A copying-book having its leaves treated with a moisture-absorbent substance and also with an antiseptic, substantially as and for the purpose shown.

4. A copying-book in which the inner parts of the leaves at the binding and an outer corner of the leaves are treated with a substance impervious to moisture, substantially as and for the purpose set forth.

5. A copying-book the leaves of which are impregnated with an absorbent for moisture and an antiseptic to prevent mildew, and have their inner edges where they are bound treated with a substance impervious to moisture, substantially as and for the purpose described.

6. In combination with the copying-book having the parts of its leaves at the binding made impervious to moisture, the moistening-pad and the two water-proof or impervious pads, substantially as and for the purpose specified.

7. In combination with the copying-book having its leaves impregnated with a moisture-absorbent and with an antiseptic, and made impervious to moisture along their parts next the binding, the moistening-pad, an impervious pad in contact with the same, and a sec-

ond impervious pad for inclosing any desired number of the leaves between it and the moistening-pad, substantially as and for the purpose shown.

5 8. The method of preparing sheets of paper for use in copying, which consists in saturating the sheets with a substance having affinity for moisture and treating it with an antiseptic to prevent mildew, substantially as and for 10 the purpose described.

9. A sheet of paper or other material for use in copying, rendered absorbent of moisture and treated with an antiseptic, for the purposes specified.

In testimony of which invention I hereunto 15 set my hand.

SAGER CHADWICK.
